UNITED STATES PATENT OFFICE.

JOHN H. IREY, OF MUSCATINE, IOWA, ASSIGNOR TO PORTABLE ELEVATOR MFG. CO.,
OF BLOOMINGTON, ILLINOIS.

VENTILATED CORNCRIB.

Continuation of application Serial No. 381,763, filed October 20, 1919. This application filed March 27, 1922. Serial No. 547,008.

To all whom it may concern:

Be it known that JOHN H. IREY, a citizen of the United States of America, residing at Muscatine, in the county of Muscatine and 5 State of Iowa, has invented certain new and useful Improvements in Ventilated Corn-cribs, of which the following is a specification.

This application is a continuation of my 10 former application, Serial No. 381,763, filed October 20, 1919.

My invention relates to corn cribs and more particularly to improvements in constructing cribs whereby ventilated spacer elements are interposed between the staves of 15 the conventional concrete silo.

The object of my invention is in the provision of a ventilated corn crib by means of interposed spacer elements between the opposed ends of adjacent staves.

Another object of my invention is in the provision of a simple spacer element which may be used in conjunction with the conventional silo stave to form a ventilated crib.

25 A further object of my invention is in the particular form of my spacer element which is capable of engaging, in a substantial manner, the opposed ends of adjacent staves and at the same time providing sufficient ventilation therebetween without detracting from the strength of the total structure.

Other objects of my invention will appear in the following specification in connection with the annexed drawings in which:

35 Figure 1, is a fragmentary vertical section of the crib structure showing the actual positioning of the spacer elements.

Figure 2, is a detail vertical section of one of the spacer elements interposed between 40 adjacent staves.

Figure 3, is a perspective view of the spacer element and

Figure 4, is a detail horizontal sectional view showing the engagement of the spacer 45 element with laterally adjacent staves.

In Figure 1 of the drawings, in which I have shown a fragmentary elevation of the corn crib, a base "a" is shown. This base portion is of concrete, although some other 50 material might well be used inasmuch as there is only the necessity of providing a substantial and level support for the stave members. The staves 10 form the major part of the wall structure of the crib and are of

conventional stave form, being comparatively long and narrow and of a thickness to correspond therewith. These staves are arranged in superposed courses and in break joint relation as I have shown in Figure 1, this structure providing a maximum of efficiency not only as to strength but as to ease of construction. As shown in Figure 4 the sides of the staves are concave and convex respectively, with the result that a cylindrical structure may be formed and the staves 65 maintained without the use of cement. Means for supporting the stave members is provided in the tie rods 11.

The structure I have so far described is merely that of the conventional concrete 70 stave silo but the essence of my invention lies in the following element:

This member has the longitudinal bars 12 which in connection with the end or head portions 13 provide the ventilating portions. 75 Projecting ears 14 on the head portions engage, as shown in the various figures of the drawings, not only the opposed ends of adjacent staves but also in a slight degree, laterally adjacent staves. Although my spacer 80 element is used in connection with the conventional silo stave, it may be seen that slight indentations 15 and 16 must be made in the adjacent staves to provide engagement portions for the ventilator member.

I have shown a specific spacer element to be interposed between the stave members but I do not wish to be limited to this particular form inasmuch as other forms might be used to accomplish the same result.

Although I have referred to the stave members 10 as those used in the conventional silo, I merely make this as a general statement and wish, in the more perfect application for my spacer element, to use it in conjunction with stave members having their opposed ends sloped to an angle of approximately forty-five (45) degrees, as shown at 17 and 18 in Figure 2, this construction of the end portions of the stave members preventing rain partially from beating through the ventilating portion.

What I claim is:

1. A ventilated corn crib including a plurality of vertically disposed staves arranged end to end in superposed courses, and grated ventilator members disposed between adjacent staves.

2. A ventilated corn crib including a plurality of vertically disposed staves arranged end to end in superposed courses and in break joint relation, means engaging the opposed ends of related staves and disposed therebetween in such manner as to form a ventilating opening therein and supporting means encircling the crib.
3. A ventilated corn crib including a plurality of vertically disposed staves arranged end to end in superposed courses, said staves having an elongated comparatively thin and narrow body with recesses formed in the ends thereof, and ventilating members disposed between the opposed ends of adjacent staves and engaging said recesses.
4. A ventilated corn crib including a plu-

rality of vertically disposed staves arranged end to end in superposed courses, said staves having an elongated comparatively thin and narrow body and with outwardly inclined upper and lower edges, and ventilator members disposed between the opposed ends of adjacent staves.

5. A ventilated corn crib including a plurality of vertically disposed staves arranged end to end in superposed courses, said staves having comparatively thin and narrow body portions and separable grating members disposed between the opposed faces of adjacent staves and acting as a means for ventilating the crib.

In testimony whereof I affix my signature.
JOHN H. IREY.
